UNITED STATES PATENT OFFICE.

ELAM RAKESTRAW, OF CAMBRIDGEPORT, MASSACHUSETTS.

COFFEE CLEANER AND GRADER.

SPECIFICATION forming part of Letters Patent No. 249,398, dated November 8, 1881.

Application filed July 15, 1881. (No model.)

To all whom it may concern:

Be it known that I, ELAM RAKESTRAW, of Cambridgeport, in the county of Middlesex and State of Massachusetts, have invented certain new and useful Improvements in Coffee-Cleaners, of which the following is a specification.

In the accompanying drawings, Figure 1 is a sectional elevation of my improvement. Fig. 10 2 is a plan view of the same, part being broken away. Fig. 3 is a sectional plan view of the same, taken through the broken line $x x x x$, Fig. 1. Fig. 4 is a rear elevation of the same, part being broken away. Fig. 5 is a sectional 15 end elevation of the same, taken through the broken line $y y y$, Fig. 3.

Similar letters of reference indicate corresponding parts.

The object of this invention is to facilitate 20 the cleaning of coffee.

The invention consists in the combination, 25 with the frame, the pivoted suspension-bars, the vibrating shoe, and the fan-blower, of the series of screens, the series of screen-boards, the shoe bottom, the four chutes, the four spouts, 30 the hinged wall, and the two partitions, whereby the whole berries and the broken and imperfect berries can be separated from each other and from impurities; also, in the combination, with the shoe-bottom, the fan-blower, the spouts, and the chutes, of the separating-partitions, whereby the whole berries and the 35 broken and imperfect berries can be subjected to separate air-blasts at the same time.

In the drawings, A represents the frame of 40 the machine.

To the top side bars of the frame A are pivoted the upper ends of the hanging-bars B, the lower ends of which are pivoted to the lower 45 part of the sides of the shoe C.

To the top of the front part of the frame A, and directly over the forwardly-projecting upper part of the shoe C, is attached the hopper D, from which the coffee is fed into the machine. As the coffee escapes from the hopper D it falls upon a screen, E, secured in the forwardly-projecting upper part of the shoe C, through which a part of the fine dirt and broken and imperfect berries escape. From the screen 50 E the coffee and the stones and coarser impurities pass over the board F, that serves as

a continuation of the screen E, and escape through an opening, G, in the flange that surrounds the said screen and board. From the board F the coffee falls upon the screen H, 55 through which the balance of the broken and imperfect berries and the fine impurities escape. The coffee and the coarser impurities slide across the screen H, and fall from the rear end of the said screen into the chute I at the rear 60 end of the shoe C, and are received upon the inclined bottom J of the said shoe C. The space above the bottom J of the shoe C is divided into two compartments by a partition, K, extending up to screen-board W, and meeting the forward extension of partition S from the wall R, and one end of the chute I is inclined, so that all that passes through the said chute will fall upon the wider part of the said bottom J. From the rear end of the bottom J 70 the coffee falls into the chute L, where it meets the air-blast through the spout M from the fan-blower N. The air-blast carries the coffee with it over the upper edge of the wall O of the chute L, and as the air-blast is weakened by 75 entering the larger space of the spout P the coffee falls through the chute Q to the floor or into a receiver placed beneath the said chute Q. The open lower part of the chute L allows 80 small stones and pieces of dirt to be separated from the coffee and fall through into some receptacle. The upper part of the wall O is loose, and is hinged at its lower edge to the upper edge of the lower stationary part of the 85 said wall, so that it can be adjusted to regulate the force of the air-blast. The lower part of the rear wall, R, of the chute Q is movable, and is hinged at its upper edge to the stationary upper part of the said wall to serve as a door to give access to the adjustable wall O. 90

The spouts M P and the chutes L Q are each divided into two compartments by a partition, S, in the same manner as the shoe bottom J. The fan-blower N is also made in two parts, as shown in Fig. 5, and its case is divided into 95 two compartments by a continuation of the partition S. The broken and imperfect berries and the fine dirt that pass through the screen E slide down the bottom board T to the front part of the screen H and pass through the said screen. All the broken and imperfect berries and the fine dirt that pass through the screen 100

H fall upon the screen-board U, slide rearwardly upon the said board, and fall from its rear end to the screen V placed beneath the said screen-board U. The fine dirt passes 5 through the screen V, falls upon the screen-board W placed beneath the said screen, and escapes through the spout X to the floor or into a receiver placed beneath the said spout X in board Y. The broken and imperfect berries 10 and any dirt too coarse to pass through the screen V fall from the front end of the said screen V through the chute Y to the bottom J of the shoe and are kept from mingling with the whole berries by the partition K. The 15 broken and imperfect berries and the dirt that did not escape through the screen V pass rearward along the bottom J and the dirt escapes through a screen, Z, secured in an opening in the said bottom J, and passes out through the 20 spout a. The broken and imperfect berries and the dirt that may be with them fall through the rear end of the narrower part of the bottom J and are operated upon and separated by the airblast in the same manner as hereinbefore described with reference to the whole berries. 25

To the front end of the shoe C is attached an arm, b, in an opening in which works an eccentric, c, attached to a shaft, d, so that the shoe C and its attachments will be vibrated by 30 the revolution of the said shaft d. The shaft d revolves in bearings attached to the frame A, and to one of its ends is attached a small pul-

ley, e, to receive a driving-belt from any convenient power. To the other end of the shaft d is attached a larger pulley, f, around which 35 passes a belt, g. The belt g also passes around a small pulley, h, attached to the shaft h' of the fan-blower N, to give motion to the fans.

Having thus fully described my invention, I claim as new and desire to secure by Letters 40 Patent—

1. In a coffee-cleaner, the combination, with the frame A, the pivoted suspension-bars B, the vibrating shoe C, and the fan-blower N, of the series of screens E H V Z, the series of 45 screen boards F T U W, the bottom J, the chutes I Y L Q, the spouts X a M P, the hinged wall O, and the partitions K S, substantially as herein shown and described, whereby the whole berries and the broken and imperfect 50 berries are separated from each other and from impurities, as set forth.

2. In a coffee-cleaner, the combination, with the shoe bottom J, the fan-blower N, the spouts M P, and the chutes L Q, of the partitions K 55 S, substantially as herein shown and described, whereby the whole berries and the broken and imperfect berries can be subjected to separate air-blasts at the same time, as set forth.

ELAM RAKESTRAW.
